COMBINED HIGH INTENSITY COSMETIC MAKE-UP LAMP AND MIRROR

Dan M. Andre, 8843 Kostner Terrace,
Skokie, Ill. 60076

Filed Apr. 22, 1968, Ser. No. 11,553

Term of patent 14 years

U.S. Cl. D48—20
Int. Cl. D26—02

FIG. 1

FIG. 2

FIG. 4

FIG. 1 is a top plan view of a high intensity cosmetic make-up lamp illustrating my design;

FIG. 2 is a rear elevational view of the same;

FIG. 3 is a side elevational view of the same; and

FIG. 4 is a front elevational view of said lamp.

I claim:

The ornamental design for a combined high intensity cosmetic make-up lamp and mirror, substantially as shown and described.
